UNITED STATES PATENT OFFICE.

WILLIAM A. GEIGER, OF CHICAGO, ILLINOIS, ASSIGNOR TO WILLIAM H. MINER, OF CHAZY, NEW YORK.

DETACHABLE DRAW-BAR AND YOKE CONNECTION.

1,286,276.

Specification of Letters Patent.

Patented Dec. 3, 1918.

Application filed February 5, 1917. Serial No. 146,587.

To all whom it may concern:

Be it known that I, WILLIAM A. GEIGER, a citizen of the United States, residing at Chicago, in the county of Cook and State of Illinois, have invented a certain new and useful Improvement in Detachable Draw-Bar and Yoke Connections, of which the following is a full, clear, concise, and exact description, reference being had to the accompanying drawings, forming a part of this specification.

This invention relates to improvements in detachable draw bar and yoke connections.

The object of the invention is to provide a simple and relatively inexpensive detachable connection for draw bars of standard type and yoke straps.

In the drawing forming a part of this specification, Figure 1 is a part longitudinal section, part side elevation of a draw bar and yoke showing my improvements in connection therewith. Figs. 2 and 3 are vertical sectional views taken on the lines 2—2 and 3—3 respectively of Fig. 1.

In said drawing 10 denotes a draw bar having a butt of usual construction, the latter having upper shoulder 11, lower shoulder 12, and vertically extending, standardly spaced rivet receiving holes 13—13. The yoke strap, designated generally by the reference A, comprises upper and lower arms 14—14, rear connecting portion 15 and filler 16. At their front ends, each of the yoke arms 14 is provided with a T-head having an outwardly extending flange 17 and an inwardly extending flange 18, the inward flanges engaging the draw bar shoulders 11 and 12. Each of said yoke arms is also provided with standardly spaced rivet receiving holes 19—19, which, when the draw bar and yoke are assembled, align with the holes

of the draw bar butt. To retain the draw bar and yoke in assembled relation, I have provided a pair of vertically extending pins 20—20, which pass through the alined holes 45 of the draw bar and yoke strap and have their ends flush with the outer surfaces of the yoke arms. To retain said pins in position, a rectangular band 21 is employed, which fits snugly around the yoke and draw 50 bar and engages at its forward edges the T-heads on the yoke strap. The rear edge of the band is designed to come flush with the rear face of the draw bar butt and is held in position by the usual front follower 55 22 of the draft gear.

With the construction above described, it is apparent that relative movement between the draw bar and yoke strap is resisted both by the pins 20 which are placed under shear 60 and the inturned flanges 18 of the T-heads. The out-turned flanges of the T-heads effectively limit the forward movement of the band relatively to the yoke and thus hold all the parts in proper position. 65

I claim:

The combination with a draw bar and yoke having alined holes, of pins penetrating said holes, and a band surrounding the yoke and draw bar butt for retaining said 70 pins in position, the ends of the yoke arms being provided with shoulders to engage the forward side of the band to limit the forward movement thereof relatively to the yoke. 75

In witness that I claim the foregoing I have hereunto subscribed my name this 31st day of Jan., 1917.

WILLIAM A. GEIGER.

Witness:

JOSEPH HARRIS.
